UNITED STATES PATENT OFFICE.

RICHARD T. CRANE, OF CHICAGO, ILLINOIS.

DESIGN FOR A GUIDE-SUPPORTING BEAM FOR ELEVATORS.

SPECIFICATION forming part of Design No. 27,827, dated November 9, 1897.

Application filed January 28, 1897. Serial No. 621,111. Term of patent 14 years.

To all whom it may concern:

Be it known that I, RICHARD T. CRANE, a citizen of the United States, residing at Chicago, county of Cook, State of Illinois, have 5 invented and produced a new and useful Design for a Guide-Supporting Beam for Elevators, of which the following, taken in connection with the accompanying drawing, is a specification.

10 The leading feature of my design consists of its peculiar configuration and outline, which comprises a beam having its middle portion bent into a **Z** shape and its ends straight and projecting in opposite directions 15 in the same plane and parallel to each other, which gives the guide-supporting beam a characteristic and distinguishing appearance.

The design is illustrated in the accompanying drawing, which represents the guide-supporting beam in the perspective.

20 The beam has its middle portion bent to a shape substantially like the letter **Z** and its

ends straight and projecting in opposite directions from the middle in the same plane horizontally, but in different planes vertically. 25

My design discloses a guide-supporting beam which presents to the eye a characteristic and distinguishing appearance, varying from other designs of guide-supporting 30 beams, particularly in having its middle portion bent in a shape substantially like the letter **Z** and its ends straight and projecting in opposite directions in the same plane horizontally, but in a different plane vertically. 35

What I claim as new, and desire to secure by Letters Patent, is—

The design for a guide-supporting beam for elevators, substantially as herein shown and described.

RICHARD T. CRANE.
